DESIGN FOR A SALT AND PEPPER SHAKER COMBINATION SET

Harriet S. Cohn, Brooklyn, N. Y.

Application January 7, 1937, Serial No. 66,933

Term of patent 7 years

To all whom it may concern:

Be it known that I, Harriet S. Cohn, a citizen of the United States, residing at No. 3051 Ocean Avenue, in the Borough of Brooklyn, county of Kings, city and State of New York, have invented a new, original, and ornamental Design for a Salt and Pepper Shaker Combination Set, of which the following is a specification, reference being had to the accompany drawing, forming part thereof.

In the drawing:

Fig. 1 is a perspective view of a salt and pepper shaker combination set showing my new design;

Fig. 2 is an end view thereof.

I claim:

The ornamental design for a salt and pepper shaker combination set, substantially as shown.

HARRIET S. COHN.
